CONNECTOR SPRING

Edward M. Armstrong, West Carrollton, Ohio, assignor to Associated Spring Corporation, Bristol, Conn., a corporation of Delaware

Application April 7, 1958, Serial No. 726,962

1 Claim. (Cl. 267—1)

This invention relates broadly to springs and spring devices and, more particularly, to a helical coil extension spring which is constructed and intended to be bent into substantially circular form and to have its ends connected in order to be maintained in such annular form while in use. Such springs have a wide variety of uses, in a typical one of which the spring device closely surrounds and engages the brush of an electrical machine and is also connected to the electrical lead to the brush, thereby providing an inexpensive, easily applied means for supplying electrical energy to the brush. This invention has to do with springs of this type and while the springs provided by the invention have general utility, they will be particularly described in this specification springs for holding the brush of an electrical machine.

It has been a particular object of this invention to provide a connector spring of the described type comprising an elongated helical coil extension spring having new and improved means formed thereon for connecting the ends of the spring and for providing for the connection of an electrical lead to the spring.

The invention is described in the following specification and illustrated in the accompanying drawing, in which:

Fig. 1 is a side elevational view of a spring device according to this invention before being formed into annular shape;

Fig. 2 is a side elevational view of one end of the spring device of Fig. 1, after being turned through 90° about the axis of the spring coil;

Fig. 3 shows the spring device of Figs. 1 and 2 formed into annular shape and having its ends connected;

Fig. 4 is side elevational view of a second embodiment of the invention;

Fig. 5 shows the spring device of Fig. 4 formed into annular shape and having its ends connected;

Fig. 6 is a side elevational view of one end of the spring device of Fig. 4, after being turned through 90° about the axis of the spring coil;

Fig. 7 is a side view of a spring device according to the invention as used to connect an electrical lead to a brush of an electrical machine;

Fig. 8 is an enlarged top plan view of the parts shown in Fig. 7, and

Fig. 9 is a view taken on line 9—9 of Fig. 8.

The present invention provides, as a new article of manufacture, a helical coil extension spring which is constructed in a new and improved manner whereby it may be bent to annular form and, by having its ends connected, be maintained in that form, in which it is useful in a very great variety and number of ways as an annular, resilient connector device. While a spring formed in accordance with this invention is of general utility, it will be described in this specification, by way of illustration, as applied to a brush of an electrical machine in order to support the brush and supply electricity to it.

2

A spring device formed in accordance with this invention is illustrated in Figs. 1 to 3 of the drawings and comprises a single length of wire formed into an elongated helical coil spring 2 having uniformly spaced, preferably 5 abutting, convolutions 4 throughout the greater part of its length, thus forming an extension spring. At one end 6 at least one, preferably two, and possibly more, of the end convolutions 8 are separated from the main body of the spring and are connected thereto by a deformed convolution 10. The space between the separated convolutions 8 and the main body of the spring is preferably approximately equal to the diameter of the wire from which the coil is formed, for a purpose which will appear hereinafter.

15 At the other end 20 of the spring coil 2 the end convolution 22 is continued tangentially of the spring coil to form a straight part 24 which extends for a substantial distance outwardly from the periphery of the spring coil and is then reversely bent through approximately 180°, 20 as shown at 26, and is then continued to form a second straight part 28 which is of such length that it preferably extends approximately to the axis of the spring coil, as shown in Fig. 1. The parts 24, 26, 28 form a U-shaped hook at one end of the spring coil which may be 25 engaged with the separated coils 8 at the other end to hold the coil in annular shape, as shown in Fig. 3. The axis of this hook, lying between the side legs 24, 28 and substantially parallel thereto, is substantially at right angles to the axis of the spring coil 2, as shown in Fig. 1 30 and in the embodiment of the invention disclosed in Figs. 1 to 3 the hook lies in a plane which is substantially parallel to the axis of the spring coil and tangential to the coil itself.

A second embodiment of the invention is disclosed in 35 Figs. 4, 5 and 6 of the drawings and is identical in construction to the embodiment disclosed in Figs. 1, 2 and 3 with the exception only of the disposition of the end hook with respect to the spring coil. In this form of the invention the end convolution 30 at one end of the 40 spring coil is continued tangentially and outwardly of the spring coil to form a straight part 32 which is then reversely bent through approximately 180°, as shown at 34, in a direction away from the axis of the spring coil, and is then continued as a straight part 36. The parts 32, 34 and 36 form a U-shaped hook in a plane substantially at right angles to the axis of the spring coil and lying 45 outside the outer periphery of the coil, as shown in Fig. 5.

In the use of a device according to the invention the spring coil formed as described above is bent into angular 50 shape and the U-shaped hook at its one end is engaged with the separated coils 8 at its other end to hold the coil in the annular shape, after which it may be used as a retaining ring for a variety of purposes. For example, as shown in Figs. 7, 8 and 9, the annular spring may surround and tightly engage the one end of a brush 40 of 55 an electrical machine (not shown). In order to effect the connection of an electrical lead 42 to the spring 2, the lead is placed alongside and in engagement with the two straight parts of the U-shaped hook and a malleable metal sleeve 44 is bent around the three parts to tightly engage and hold them in contact with each other and prevent their separation.

The spring device provided by this invention may be 60 easily and cheaply manufactured on known machines and may also be shaped to annular form on such machines. The provision of a U-shaped hook at its one end and one or more separated convolutions at the other end permit quick and simple, but releasable, connection of the two ends of the spring.

70 While I have described and illustrated certain embodiments of my invention it will be apparent to those skilled

in the arts to which it relates that other embodiments, as well as modifications of those disclosed, may be made and practised without departing in any way from the spirit or scope of the invention, for the limits of which reference must be made to the appended claim.

What is claimed is:

As a new article of manufacture, a spring device comprising a helical coil extension spring the convolutions of which have uniform pitch throughout the greater part of the length of the coil, and at its one end having at least one convolution spaced axially outwardly from the main body of the coil, the end convolution at the other end of the coil being extended tangentially outwardly from the coil and formed into a U-shaped hook hooked through the outwardly spaced convolutions at the other

end of the coil to connect the ends of the coil and maintain the coil in annular shape, said hook lying in a plane at right angles to the axis of the coil and outside the periphery of the coil.
